(57) **CLAIM**

The ornamental design for a harness patch, as shown and described.

DESCRIPTION

FIG. 1 is a perspective view of my new design for a harness patch in use, mounted to a harness. The portions of the harness that form no part of the claimed design are shown in broken lines.

FIG. 2 is a top plan view of the harness patch thereof;

FIG. 3 is bottom plan view thereof;

FIG. 4 is a rear view thereof;

FIG. 5 is a front view thereof;

FIG. 6 is a left side view thereof;

FIG. 7 is right side view thereof; and

FIG. 8 is a perspective view thereof, in use mounted to a harness worn by an animal.

The portions of the harness and the animal that are shown in broken lines form no part of the claimed design.
